UNITED STATES PATENT OFFICE.

CHARLES D. BARRETT, OF ALTOONA, PENNSYLVANIA.

SMOKE BOX FOR LOCOMOTIVES.

Application filed December 28, 1926. Serial No. 157,598.

My invention relates to locomotives or similar boilers to be operated under a forced draft and particularly to an improved and efficient arrangement of the elements of a smoke-box for locomotives, and to a method of controlling the draft to insure proper steaming function of the boiler.

In the smoke-box of an ordinary locomotive there will be an accumulation of cinders underneath the stack, or in the front end of the smoke-box away from the flue-head. It is, therefore, necessary to clean out the smoke-box frequently in order to prevent the accumulation from partially obstructing the draft unless the smoke-box is specially designed to be "self-cleaning". It has been found possible by a rather elaborate arrangement of baffles or deflector plates to so direct the furnace draft over the bottom surface of the smoke-box as to sweep the cinders up the stack and this has been termed a "self-cleaning" smoke-box.

The usual type of self-cleaning smoke-box has the objection that the deflector or diaphragm plates and spark-arrester netting must be carefully fitted against the sides of the smoke-box and around the exhaust nozzle in order to control the draft and prevent the discharge of cinders into the stack without passing through the netting. As the smoke-box is usually circular in cross-section and it is necessary to avoid the various steam pipes and headers located partially or wholly within the box, it has been a difficult and expensive matter to arrange the diaphragm plates and netting to secure the desired results.

It is an object of my invention to provide an efficient self-cleaning smoke-box of simpler construction than those heretofore used.

A further object of my invention is to provide a deflector plate which does not require fitting to the outlines of the smoke-box and to the exhaust nozzle, and which will produce the desired velocity of the furnace gases in the smoke-box necessary to prevent the accumulation of the cinders therein and to insure proper draft in the stack to the end that the boiler will show the necessary and required steaming characteristics.

In accordance with my invention, a smoke-box which is self-cleaning and which assures proper draft conditions, is secured by the use of a deflector or baffle plate which, in its preferred form, is of substantially cylindrical shape and is suspended from a depend-

ing lift or petticoat pipe extension of the stack and within the smoke-box. It is a relatively simple matter to mount such a deflector plate in position being readily accessible from the front door opening of a locomotive and, by reason of its cylindrical form, to secure a tight fit between all the elements of the construction. The spark-arrester netting may be circular or cup-shaped and may be suitably secured at its upper end to the bottom of the lift pipe, while at its lower end it surrounds and contacts with the upper edge of the exhaust nozzle.

The deflector plate is of somewhat larger diameter than the lift pipe and extends downwardly to a point adjacent the bottom of the smoke-box, leaving a restricted opening for the products of combustion passing from the flues to the stack. To insure the requisite velocity for the gases passing to the deflector plate, the total area of the restricted opening is substantially equal to or somewhat less than the total fire area through the flues in the boiler. In order to equalize the flow of gases into the stack, it has been found preferable in some cases to space the deflector plate somewhat further from the bottom of the smoke-box on its front side. In this manner, an efficient construction of self-cleaning smoke-box may be obtained with a deflector plate that is easily mounted in operative position.

In the accompanying drawings, I have shown one embodiment of my invention as applied to a locomotive boiler which is otherwise of standard construction in order to provide a full and clear disclosure thereof.

Referring to the drawings:

Fig. 1 is a horizontal sectional view along the section line 1-1 of Fig. 2, of the smoke-box of a locomotive boiler embodying my invention;

Figs. 2 and 3 are vertical sectional views of the smoke-box shown in Fig. 1, along the longitudinal and transverse axes of the boiler, respectively, with portions of the boiler and superheater shown in elevation.

Fig. 4 is a diagrammatic view of a smoke-box showing the preferred arrangement of the boiler, exhaust and blower nozzles, deflector plate and stack with certain details omitted for the sake of clearness, and

Figs. 5, 6 and 7 are detail views of the deflector plate assembly.

The locomotive boiler shown in Figs. 1-3

is, with the exception of the smoke-box, of standard construction and comprises a shell or waist 1, closed by the usual tube sheet 2, the latter supporting a plurality of flues or fire-tubes 3 through which the products of combustion pass from the fire-box into a smoke-box 4, at the forward end of the boiler shell, and thence to the atmosphere through a stack 5. The steam supply 10 from the boiler flows through the usual dry pipe 6, into a superheater header 7, and thence through the superheater tubes 8 to the supply pipes 9. An exhaust nozzle 10 of the usual construction projects upwardly 15 through the bottom of the smoke-box 4 directly beneath the stack 5.

A lift or petticoat pipe 12 is secured at its upper end to the stack 5 and constitutes, in effect, an extension thereof toward the bottom of the smoke-box. A substantially cylindrical deflector or diaphragm plate 13 of greater diameter than the diameter of the lift pipe 12, is supported thereon and extends to a point adjacent the bottom of the smoke-box. The lift pipe 12 is carefully fitted to the stack and to the depending deflector plate and both the lift pipe and deflector plate are imperforate, so that the products of combustion are prevented from 25 entering the stack except underneath the lower edge of the deflector plate at the bottom of the smoke-box.

The foregoing elements of the improved boiler and smoke-box are indicated in outline in Fig. 4 and reference may be had to this figure for an explanation of the underlying principles of the invention before considering the constructional details shown in the other figures of the drawing. As indicated in Fig. 4, the deflector plate 13 extends below the top of the exhaust nozzle 10, so that the opening through which the products of combustion pass into the stack is restricted in area. It is usually advisable 40 to space the bottom of the deflector plate further from the bottom of the smoke-box on the side away from the flues, as shown, in order to more nearly equalize the flow of gases into the stack, although in some cases 50 this arrangement may be found unnecessary.

On account of the restricted opening into the interior of the deflector plate which forms, in effect, an extension of the stack, the relatively high velocity of the gases carries the cinders into the stack and prevents an accumulation thereof in the bottom of the smoke-box. Furthermore, it has been found that the effect upon the draft is such that the boiler shows the required steaming characteristics. In order to insure this result, it has been found necessary in actual practice to restrict the opening to an area substantially equal to or less than the total fire area through the boiler flues. In one instance, successful operation was obtained

with an opening of approximately 917 square inches where the area of the gas passage through the flues was 1138 square inches.

Other elements of the smoke-box cooperating with the deflector plate in the modification shown include a blower nozzle 18 and a spark-arrester netting 19. The blower-nozzle 18 comprises a hollow ring-shaped casting of the form shown, and utilized to perform the additional function of a coupling or connecting member between the lift pipe 12 and the deflector plate 13. The arrangement and location of the blower nozzle is a matter of choice and frequently it is located at some other point or combined with the exhaust nozzle.

The spark-arrester netting 19 may also be supported by the blower casting and surrounds and embraces the upper end of the exhaust nozzle 10 to prevent the entrance of sparks around the periphery of the nozzle. The netting need not be secured in any way to the nozzle 10 provided it is fitted tightly enough to accomplish the desired results. The deflector plate may be flattened or bent, if necessary to clear the superheater tubes 8, without interfering in any way with the operation of the smoke-box nor increasing the cost of the construction or the difficulty of assembling it. Such a flattening of the deflector plate is shown in Fig. 1, the purpose being to avoid interference with the superheater tubes 8.

The several elements of the construction described may be secured in assembled relation and mounted upon the boiler shell in any suitable manner. As shown in Figs. 1 to 3, the lift pipe, the deflector plate, the spark-arrester netting and the blower nozzle form a unit which may be conveniently inserted in the smoke-box, through the front door opening thereof and secured in position by the braces 25 and bolts or rivets 26.

The blower casting 18, is bolted or riveted to the lift pipe 12, and the deflector plate and spark-arrester netting 19 are supported at their upper ends from this casting. As shown in Fig. 5, the casting 18 supports a plate or ring member 27 to which the spark-arrester netting may be welded, as indicated at 28. A bolt 29 provided with a removable key 30 secures the ring member 27 to the blower casting, a spacing ring 31 being interposed between the ring member and casting. Upon removal of the key 30, the structure may be readily disassembled. A series of bolts such as is shown in Fig. 5, is provided around the periphery of the deflector plate assembly, as indicated in Fig. 1.

The deflector plate 13 is supported from the blower casting in a similar manner, as shown in Fig. 6. The deflector plate is

provided with an internal lip 32 adapted to rest upon the periphery of the blower casting 18 and to be held in such relation by a bolt 33 and removable locking key 34. A series of holding bolts is provided around the periphery of the casting, and the plate may be formed in sections, as shown in Fig. 1, to facilitate the assembly. Any suitable means for securing the elements of my invention together may, of course, be used in place of that shown.

The blower nozzle 18 is provided with an inlet opening 35 (see Fig. 2) and a series of upwardly directed outlets 36 (see Fig. 7) to produce a draft through the fire-box, flues and stack when steam is admitted to the blower.

I am aware that certain modifications of the structure which I have shown and described may occur to those skilled in the art and consequently I desire that my invention shall not be limited in scope except as limitations may appear in the appended claims.

25 I claim:

1. In a locomotive boiler having a smoke-box into which the boiler flues or fire tubes discharge the products of combustion and a stack for conducting and discharging the said products from the smoke-box to atmosphere, means including a deflector plate that is out of contact with the side walls of the smoke-box and extends from the stack to a point adjacent the bottom of the smoke-box and completely closes the path for the products of combustion from the flues to the stack except for a restricted area between the bottom of the deflector plate and the bottom of the smoke-box, which area is substantially equal to or less than the total area of the gas passage through the flues.

2. In a locomotive boiler having a smoke-box into which the boiler flues or fire tubes discharge the products of combustion, an exhaust steam nozzle positioned at the bottom of the smoke-box, and a stack at the top thereof in vertical alignment with the exhaust nozzle, means including a deflector plate suspended from the stack and extending slightly below the upper end of the exhaust nozzle, the deflector plate being circumferentially closed and arranged to constitute, in effect, a stack extension to close completely the path for the products of combustion from the flues to the stack except for a restricted area between the bottom of the deflector plate and the bottom of the smoke-box, which area is substantially equal to or

less than the total area of the gas passage through the flues.

3. In a locomotive boiler having a smoke-box into which the boiler flues or fire tubes discharge the products of combustion, an exhaust steam nozzle positioned at the bottom of the smoke-box and a stack at the top thereof and in vertical alignment with the exhaust nozzle, the combination of a lift pipe suspended from the stack which constitutes, in effect, an extension thereof and having a depending deflector plate suspended thereon and conforming generally to the outline thereof, a blower nozzle positioned to cooperate with said lift pipe and a spark-arrester screen secured at one end to said deflector plate and at the other end to the exhaust nozzle, the deflector plate and lift pipe being arranged to close completely the path for the products of combustion from the flues to the stack except for a restricted area between the bottom of the deflector plate and the bottom of the smoke-box, which area is substantially equal to or slightly less than the area of the gas passage through the flues.

4. In a locomotive boiler having a smoke-box into which the boiler flues or fire tubes discharge the products of combustion, the combination of an exhaust steam nozzle at the bottom of the smoke-box, a stack at the top thereof and in vertical alignment with the exhaust nozzle and means including a deflector plate supported independently of the side walls of the smoke-box and extending from the stack to a point adjacent the bottom of the smoke box and below the top of the exhaust nozzle, the deflector plate being spaced further from the bottom of the smoke-box at the front than at other points of its bottom edge but forming a restricted opening between the smoke-box and the stack, the area of said opening being substantially equal to or slightly less than the total area of the gas passage through the flues to produce a sufficiently high velocity of the furnace gases to render the smoke-box self-cleaning and insure proper steaming function of the boiler.

5. A method of controlling the draft in the smoke-box of a locomotive which comprises passing the products of combustion to the stack through a restricted passage the area of which is substantially equal to or slightly less than the fire area through the tubes.

CHARLES D. BARRETT.
